2 Claims

ABSTRACT OF THE DISCLOSURE

A stylographic writing pen, whereby a reinforced barrel nib jacket acts as the pen stylus in the capillary passage of which stylus a cleaning stem is reciprocably movable.

FIELD OF THE INVENTION

This invention is such as to encompass all stylographic pens, be they for drafting or scribing.

SUMMARY OF THE INVENTION

According to the present invention, the writing pen comprises a barrel with barrel nib, the bottom of which is provided with a cover, the cover being a deep stress product which is made of sheet metal. The bottom of this cover acts as the pen stylus, per se. Through the capillary passage of said stylus, the cleaning wire of the pen is reciprocably movable, to clean it.

BRIEF DESCRIPTION OF THE DRAWINGS

FIG. 1 is a view in side elevation of the stylographic writing pen according to the invention;

FIG. 2 is an enlarged fragmentary vertical section view of the pen according to FIG. 1;

FIG. 3 is an enlarged fragmentary vertical sectional view of a pen nib of the pen taken along lines 3—3 of FIG. 2;

FIG. 4 is an enlarged transverse sectional view of the basic construction writing pen taken along section lines 4—4 of FIG. 2;

FIG. 5 is an enlarged fragmentary bottom view of the stylographic writing pen according to FIGS. 1—3; and

FIG. 6 is an enlarged fragmentary view of a modified bottom part of the stylographic writing pen according to FIGS. 1—3.

DESCRIPTION OF THE PREFERRED EMBODIMENTS

In FIG. 1 the stylographic writing pen 10 is shown with barrel 12. The writing nib 14 of the pen is provided with the reinforced bottom 16, which is also shown in FIGS. 2, 3 and 4. Reference FIG. 2, the lower side wall 20 of the writing nib 14 is offset recessed and in recess 18, the cover 16 is set, which during assembly is attached to the writing nib 14 by means of glue or cement.

In another embodiment, the cover 16 is provided with an inward directed rim 21 as indicated by phantom lines,

2

enabling the cover 16 to be connected to the writing nib 14 during the molding of this nib.

Tubular extension 22 of the cover 16 acts as the pen stylus, its passageway 24 being longitudinally aligned with passageway 26 in the writing nib 14.

As the stylus bottom 30 has a more or less rectangular transverse section, the passageway 24 and the stylus opening 28, are each circular as indicated in FIG. 5. In another embodiment, FIG. 6, both passageway 24' and opening 28' are likewise rectangularly sectioned.

In practice, the cover 16 is made of sheet metal, such as steel or stainless steel. It should be hardened, at least in part coextensive with the pen stylus portion 22.

Cover 16 may be alternately fashioned of a malleable and easily formed material and thereafter plated with nickel, chrome or other hard alloy. In either event, cover 16 is a deep stress product. In the first instance of its fabrication, its bottom 30 is closed, having a wall thickness as indicated by the phantom lines (FIG. 2). Bottom 30 is connected with the side wall 34 of the stylus, forming outside radii 36. In the next phase of production, hole 28 is bored in bottom 30.

As shown in FIG. 4, a section of cover 16 is oval shaped with the widest measurements being at side wall 25 parts 38, a cross-section of the cover over these side walls 38 being shown in FIG. 3.

The present reinforced cover construction enables ink passage 26 and ink chamber 40 to be positioned in the molded writing nib 14 with less than minimal cost of pen production, considering the prior art. Furthermore, there is provided herein an ideal guide for the cleaning wire 42 from the upper ink chamber 44 into the ink chamber 40, via the inclined inner reservoir wall 46 and from the ink chamber 40 via the inclined inner wall 48 into ink passage 26, which guide prevents damage of the cleaning wire 42, during re-assembly and forced reciprocation of this wire in cleaning.

I claim:

1. In stylographic pens having integral reservoir, connecting capillary nib and reciprocal cleaning wire for the nib, the improvement comprising: reinforcing nib jacket, exteriorly set about the nib, the said jacket defining a capillary ink stylus at its terminal end.
2. The improvement of claim 1 in which the jacket consists of a deep stress material, said jacket having an end which is in extenso of the capillary nib and in alignment therewith.
